United States Patent Office

Des. 233,768
Patented Nov. 26, 1974

233,768

FENCE PANEL OR THE LIKE

Wayne L. Wilder, 3005 Oradell,
Dallas, Tex. 75220

Filed Jan. 22, 1973, Ser. No. 325,332

Term of patent 14 years

Int. Cl. D25—01

U.S. Cl. D28—1 A

FIG. 1

FIG. 3

FIG. 2

FIG. 4

FIG. 1 is a front perspective view of the fence panel or the like, in accordance with my new design;

FIG. 2 is a rear perspective view of the invention illustrated in FIG. 1;

FIG. 3 is a section taken on line 3—3 of FIG. 1, looking in the direction of the arrows; and

FIG. 4 is a section taken of line 4—4 of FIG. 1, looking in the direction of the arrows.

FIGS. 3 and 4 have been shown foreshortened for convenience of illustration.

I claim:

The ornamental design for a fence panel or the like, substantially as shown and described.
